UNITED STATES PATENT OFFICE.

THOMAS B. WILLIAMS, OF ORANGE, MASSACHUSETTS, ASSIGNOR TO LEAVITT MACHINE COMPANY, OF ORANGE, MASSACHUSETTS, A CORPORATION OF MASSACHUSETTS.

MACHINE FOR RESEATING VALVES, &c.

No. 918,805.

Specification of Letters Patent.

Patented April 20, 1909.

Application filed January 17, 1906. Serial No. 296,442.

To all whom it may concern:

Be it known that I, THOMAS B. WILLIAMS, a citizen of the United States, and a resident of Orange, in the county of Franklin and State of Massachusetts, have invented certain new and useful Improvements in Machines for Reseating Valves, &c., of which the following is a specification.

This invention relates to an improved machine for reseating valves, etc., and the principal object of the invention is to provide an improved machine of this character by means of which the truing up or facing of valves and valve-disks of all kinds can be readily accomplished, and which will also be capable of operating in a similar or analogous manner upon other work.

Various machines of this general character have been designed and are in general use. My improvements thereover relate more particularly to a machine of this character in which the tool and tool-holder have a wider range of movement and adjustability than has been the case heretofore, this range being such in my improved machine that the tool and the tool-holder are practically universally movable with respect to the work. This result is preferably accomplished by mounting the tool-holder on an arm carried by the standard which supports the work-holder and having its axis extending in substantially the same direction as the axis of the work-holder, the tool-holder being mounted on this arm in such a manner as to be movable about the axis thereof, and preferably in all other directions in which movement of the tool is desirable. In the preferred construction the arm which extends from the standard that supports the work-holder has its longitudinal axis parallel with that of the work-holder and carries a tail-support on which the tool-holder is mounted and on which it may have all necessary adjustments and feed movements. This tail-support may be located outside of and beyond the tail-stock by means of which the work is supported, both the tail-stock and the tail-support being preferably mounted on and adjustable along the same arm. Other features of my invention which relate to the construction, organization and mode of operation of the various parts for adjusting and feeding the tool-holder and the tail-support, to means for obtaining a quick or a gradual adjustment of the posi-

tion of the tool, and various other matters, will be hereinafter described, and are illustrated in the accompanying drawings, in which—

Figure 1 is a sectional elevation of a complete reseating machine constructed in accordance with my present invention and illustrating the parts in position for operating upon a valve-disk; Fig. 2 is a plan of the same showing various adjustments of the tool-holder and its feed-slide on the tail-support; Fig. 3 is an enlarged transverse section and end elevation of the tail-stock and the tail-support, with the parts mounted thereon, as seen from the right in Fig. 1; Fig. 4 is a sectional detail of the same, the section being taken in the line 4—4, Fig. 3, looking in the direction of the arrow; Fig. 5 is a detail of the means for feeding the tool in a curvilinear path or a rectilinear path, as desired; Figs. 6 and 7 are details of the means for effecting a quick or a gradual adjustment of the position of the tool-holder; Fig. 8 is a detail corresponding to Fig. 5 and showing the positions of the tool-slide and coöperative parts when a rectilinear movement of the tool is desired.

Similar characters designate like parts in all the figures of the drawings.

All of the various parts of the machine except the tail-support and the devices carried thereby may be of well-known construction, and as shown are substantially similar to corresponding parts of similar machines now in general use. The main frame of the machine shown herein is the usual standard comprising an open ring 1 and a squared lug 2 depending therefrom for engagement between the jaws of a bench-vise 3 in the well-known manner, although of course an independent supporting frame may be used. The ring 1 is internally threaded for engagement by the correspondingly threaded gripping jaws 5 of a chuck 4 through which passes a work-spindle 6 having at one end a work-holding chuck 7 and at its other end means for turning the work-spindle. The chucks 4 and 7 may be of similar construction, each having a knurled adjusting collar for the purpose of shifting the gripping jaws 5 and 8 radially. These adjusting collars are indicated at 9 and 10. These chucks being of well-known construction, and the means for spreading and drawing in the gripping jaws being old and well known, these parts will not be further described.

The work-spindle 6 is journaled in the chuck body and also passes through a hub 11 constituting an extension of said chuck body. This hub is split for a considerable distance 5 at its outer end and is both externally and internally threaded at such end. It also has an internal bore of considerably greater diameter than the diameter of the work-spindle where the spindle passes through such hub, a 10 sleeve, which constitutes a bushing or bearing for the spindle, being located between the spindle and the hub 11 throughout the length of said hub. This intermediate sleeve, which is designated by 12, is externally threaded 15 and terminates at its outer end in a hand-wheel 13 by means of which the sleeve 12 is turned. The external threads of said sleeve engage with the internal threads of the hub 11, and when the hand-wheel 13 is turned the 20 sleeve 12 will be shifted longitudinally in one direction or the other. The work-spindle 6 is reduced in diameter where it passes through the sleeve 12, and the inner end of said sleeve is stopped by a washer 14 abutting 25 against the stop-wall separating the different diameters of the work-spindle, the outer end of the sleeve 12 being stopped by the hub of a second hand-wheel 15 secured to the end of the work-spindle by a lock-nut 16, said hand-wheel being intended to turn said 30 spindle. A detachable crank 17 is provided for reducing the labor of turning the work-spindle when a piece of work is being faced by the tool. From the construction of the 35 parts just described it will be seen that while the sleeve 12 and the work-spindle 6 are free to turn relatively to each other, they have no relative longitudinal movement. The work-spindle is, however, adjusted longitudinally 40 by means of the sleeve 12, this being effected by turning the hand-wheel 13 to the right or the left as desired to feed the work up to or withdraw it from the tool. When the spindle 6 is in proper working position it may be 45 locked against further lengthwise movement by means of a locking collar 18 internally threaded and engaging the external threads at the end of the sleeve 11. This collar when turned to the right draws together the split 50 sections at the threaded end of the hub 11 and locks the hub 11 and the sleeve 12 together, so that the hand-wheel 13 and the sleeve 12 can not be turned.

All of the usual parts of a valve-reseating 55 machine, especially as adapted for facing a valve-disk, such as *d*, have now been described, with the exception of the tail-stock and the arm by which the tail-stock is supported. This tail-stock is shown at 19 and 60 may be of any suitable or usual construction adapted to be secured to an arm extending from the standard formed by the ring and lug 1 and 2. This arm projects from said standard in such a manner that its longitudinal axis extends in the same general direction

as, and is preferably parallel with, the longitudinal axis of the work-holder and work-spindle. As here shown, this arm is a rod 20 having a journal surface on which the parts carried by the arm may be turned to different positions about the axis of said arm. 70

The principal novel parts of my improved machine are embodied in a tail-support carried by the arm 20. In the construction shown this tail-support is located outside of, 75 that is, beyond, the tail-stock 19 and its center-pin 19'. The tail-support as a whole may be turned on the journal surface of the arm 20 to various positions, and it may be clamped in place in any position to which it 80 may be turned. The main element of this tail-support is a bracket-arm 21 having a divided hub which may be securely fastened to the arm 20 by a clamping-screw 22. This bracket-arm constitutes a guide on which 85 the other parts of the tail-support may be adjusted toward and from the axis of the work-holder. The principal element of the tail-support, which is movable with respect to the bracket-arm, is a block 24 having a 90 clamping-screw 25, the shank of which passes through a long slot 23 in the bracket-arm 21. This block may be slid to any desired position on the bracket-arm, and when located 95 may be clamped in place by the screw 25. The block 24 is substantially T-shaped in elevation, and the head of the block forms a substantially semi-circular table on which 100 rests a similarly shaped plate 26 constituting the principal element of a swivel by means of which the tool-holder and other parts may be adjusted about an axis perpendicular to a plane in which the axis of the work-holder lies. The edges of the plate 26 and the table 105 of the block 24 may be indexed, if desired, in order to obtain an accurate angular adjustment or indexing movement of the swivel and tool-holder with respect to the block 24. Normally the movement of the plate 26 of the swivel is confined to an arc limited by a 110 pair of stops 27 and 28 set in the edge of the table of the block 24, a stop 29 on the plate 26 normally working between said stops. However, a greater range of movement may 115 be had whenever desired by raising the plate 26 from the table of the block 24 and turning said plate until the stop 29 is outside of the stops 27 and 28. This may be accomplished by loosening to the proper extent a lock-nut 30 at the threaded lower end of a bolt 31 120 journaled in a vertical bearing in the block 24 and normally serving to clamp the plate 26 and the block 24 together. This will be obvious by referring to Fig. 4. This bolt 31 constitutes the vertical pivot about which 125 the swivel and the parts supported thereby turn.

At its upper side the swivel-plate 26 has an undercut guideway in which is supported a substantially oblong slide-block 32. This 130

slide-block may be shifted to any desired position on the plate 26 and clamped in place by a set-screw 33 and a gib 34. Said block constitutes the other main element of the swivel, 5 which, as shown, is a two-part swivel having a block or head adjustable with respect to the main portion or plate of the swivel. The slide-block is formed at its upper and lower sides with beveled ways, such as 35 and 36, 10 which coact with corresponding guideways or grooves, the ways 35 coacting with those of the channel in the upper face of the plate 26, while the ways 36 coact with corresponding beveled ways of a channel in the under side 15 of a feed-slide mounted on and movable longitudinally of the slide-block 32. This feed-slide is designated generally by 37. It is adapted to be fed gradually along the ways 36 of the slide-block 32 for the purpose of im- 20 parting the proper feed movement to the cutting tool. Any suitable feeding means may be employed for this purpose, but I prefer to make use of a feed-screw, such as 38, of the well-known type, journaled at one end 25 in one end of the slide-block and at its other end in a plate 39 which is here shown as screwed to the other end of the slide-block. A hand-wheel 40 is secured to one end of the feed-screw for the purpose of turning the 30 same. The means for imparting the rotary movement of the feed-screw to the feed-slide as a longitudinal movement of the latter is here shown as a block 41 screw-threaded at its inner edge and mounted to slide 35 back and forth in a rectangular opening in the feed-slide in a direction transverse to the feed-screw. The object of this is to effect the usual gradual feed of the feed-slide when the block 41 is coupled to the feed-slide while 40 permitting a quick adjustment of the feed-slide to any desired position whenever the feed-screw and said block are disengaged. For the purpose of effecting the connection and disconnection of these two parts I have 45 shown a lever having its pivot in a rock-shaft 42 on the feed-slide and having a short arm 43 which depends into a recess 45 in the upper side of the block 41, the long arm 44 of said lever projecting outside the feed-slide 50 and constituting the means for turning the rock-arm 42. The arm 44 of this device, as shown in Fig. 7, is normally at one side of a stop 46 on the feed-slide, and in such position couples the feed-screw and the block 41. 55 Said lever, however, is sufficiently resilient to be sprung to the other side of said stop, and when in such position uncouples the block 41 from said feed-screw. The feed-slide also supports a cross-feed tool-slide, 60 which is designated generally by 47. This tool-slide is mounted in a transverse dovetail channel in the upper side of the feed-slide. Normally said tool-slide has no cross-feed movement and is so held that its only 65 movement is a feed movement in unison with

the feed-slide 37. At such a time the position of the tool-slide is that indicated in Fig. 8, in which the tool-slide is shown as drawn out to the extreme right-hand end of its range of transverse movement on the feed- 70 slide. In order to hold the tool-slide in that position a stop or detent in the form of a swinging-latch 48 is mounted on the tool-slide, this latch being movable into engagement with a stop-wall on the feed-slide. The 75 stop-wall shown is the head of an adjusting-screw 49, which is screwed directly into the feed-slide transversely and at the under side of its head presses against a pin 50 seated in a transverse bore 51 in the tool-slide, which 80 bore contains a coiled spring encircling the shank of said pin 50. By turning the adjusting-screw 49 to the right or the left the tension of the spring 52 surrounding said pin may be increased or decreased as desired. 85 The function of this spring, when properly tensioned, is to force the tool-slide to the left, as shown in Fig. 5, and the spring should be of sufficient length and under sufficient tension at all times to permit it to force said 90 tool-slide to its extreme position to the left as seen in said view. Normally, however, the tool-slide is pressed to the right, and when in its extreme right-hand position is latched there by swinging the latch 48 down 95 into contact with the wide head of the adjusting-screw 49. The latch 48 is recessed at 53 to permit it to be hooked over the shank of the screw 54 on the tool-slide which constitutes a stop for 100 bracing the latch 48 and holding it rigidly at a right angle to the tool-slide. When said latch is swung up, as shown in Figs. 3, 4 and 5, the spring 52 expands and instantly forces the tool-slide 47 to the left, as seen in Fig. 5. 105 When this occurs a follower-pin 55, which is seated in a longitudinal bore in the tool-slide, is brought into contact with a guide on the slide-block 32 and determines the extent of movement of said tool-slide to the left, as 110 shown in Fig. 5. The guide with which said pin comes in contact is here shown as a metallic strip 56 secured by screws 57 to the upper surface of the slide-block in the direction of the length thereof. This guide as shown 115 has one or more curvilinear guide-faces. One of these is indicated at 58 and another is shown at 59. These two curved guide-faces are defined by arcs of different circles. The approaches to said curved guide-faces are by 120 way of straight cam faces, designated by 60. In the position shown in Fig. 5 the follower-pin 55 is in contact with one of these straight cam faces 60. As a feed movement is imparted to the feed-slide 37 on the turning of the hand-wheel 40 to the right, the pin 55 will follow the surfaces 60 and 58 or 59 with which it may be in contact, and the tool-slide 125 will be fed in a path corresponding to the contour of the guide-face with which the fol- 130

- lower-pin is in contact. If said pin 55 is in contact with the curved face 58 the tool-slide 47 and the cutting tool carried thereby will have a feed movement corresponding to the 5 curve which defines the face 58. If the follower-pin is in contact with the face 59 the path of feed movement of the cutting tool will correspond to the curve defining the 10 guide-face 59. One or the other of these faces may be brought into action as desired by releasing the screws 57, when either the 15 guide-face 58 or the guide-face 59 may be presented toward the work and the guide then clamped in place.
- 15 The tool-slide supports a tool-holder which is designated generally by 61 and which has a swinging movement about a vertical axis passing through the tool-slide. This tool-holder may be secured in different positions 20 pivotally on the tool-slide and clamped firmly in any angular position to which it may be adjusted. For these purposes a clamp-screw 62 passes through the tool-holder into either one of a pair of tapped 25 holes 64 in the tool-slide. When screwed home this screw holds the tool-holder firmly in the desired angular position and also locks the cutting tool, which is indicated at *c*, to the tool-holder and the tool-slide.
- 30 As indicated by the full-line and dotted positions of the slide-block, etc., in Fig. 2, it will be seen that by means of a tail-support of the type herein described a cutting tool may be adjusted to a great variety of posi-

tions with respect to the work. It will also 35 be evident that all kinds of angular faces may be cut or faced by my improved machine, whether said faces be straight, tapered or rounding. By mounting the parts in the manner described a very rigid support for the 40 work and the tool is obtained, the tail-stock and the tail-support being mounted so close together on the same support that there is no chance for the parts to chatter and impair the accuracy of the cutting operation, which 45 is a matter of great importance in reseating valves and valve-disks.

What I claim is:

In a machine of the character described, the combination with a rotary work-holder, 50 and with a standard for supporting the same, of an arm extending from said standard and having an axis substantially parallel with that of the work-holder, a tail-stock carried by said arm and co-operative with said work-holder, and a tail-support also carried by said arm beyond the tail-stock and embodying means lapping the tail-stock lengthwise of said arm for moving a tool into the plane 55 and into engagement with the work. 60

Signed at Orange in the county of Franklin and State of Massachusetts this 12th day of January A. D. 1906.

THOMAS B. WILLIAMS.
